UNITED STATES PATENT OFFICE

2,466,456

GEAR ACTUATED WRENCH

Benjamin H. Lybyer, Casper, Wyo., assignor of
fifty per cent to Wayne M. Roberts, Ada, Okla.

Application July 19, 1945, Serial No. 605,873

2 Claims. (Cl. 81—57)

1

This invention relates to improvements in wrenches and has for an object to provide a gear actuated wrench.

Another object of my invention is to provide a crank actuated gear drive wrench.

A further object of this invention is to provide a chain driven wrench.

A still further object of the invention is to provide a wrench which may be used in close spaces where other wrenches cannot be operated.

Other features and advantages will become more readily apparent from the following description and the accompanying illustrative drawings in which:

Figure 1 is an elevational view partly in section of my wrench,

Figure 2 is another similar view thereof, taken from a different angle,

Figure 3 is a side elevational view of a modification,

Figure 4 is another elevational view thereof,

Figure 5 is a detail view of a crank handle therefor, and

Figure 6 is a detail of a socket wrench plug.

In the specification to follow and in the several views in the drawings like reference characters indicate like parts throughout and in which 10 and 11, indicate two forms respectively of my improved wrench and in form 10, I provide a housing 12, consisting of two longitudinal sections 13 and 14, each having a semi-cylindrical channel 15 and 16, which when these members are connected and secured together form a cylindrical bore 17, through which extends a cylindrical shaft 18, the lower end 19 of which is enlarged in diameter and is provided with integral threads to form a worm 20.

The upper end 21, (shown dotted) is squared and fits into a similar opening in the crank handle 22, wherein it is held by a screw 23, also shown dotted. Below the handle and encompassing the upper ends 24 and 25, of the sections 13 and 14, is a thimble 26. A weighted end 27, is provided on the shank end 28, opposite the handle 29, is provided for balancing and facilitating the turning of the handle 22. The thimble 26, together with a slidable collar 30, on the member 12, coact to hold said sections 12 and 13, secured together. However, upon removal of the thimble and collar the device automatically becomes disassembled. The member 12, tapers from top to bottom end.

The said members 13 and 14, both terminate in inclined outwardly spaced walls 31 and 32, between which is mounted a worm gear 33, pro-

2

vided with a rectangular aperture 34, aligning with larger cylindrical bores 35 and 36, through said walls 31 and 32. The aperture 34, is adapted to receive the shank 37, of a socket wrench plug 38, the latter being provided with a spring pressed ball 39, to seat in a provided recess, in the socket wrench. Ball bearings 39", (shown dotted) are provided for the upper and lower ends of the shaft 18.

10 In Figures 3 to 5, I show a modification of the above described wrench which consists of a pair of spaced plates 40 and 41, connected by spacers 42 and 43, and screws 44 and 45. These plates terminate at their outer ends 46 and 47, in handles 48' and 49, between which may be provided a filler if desired.

Mounted between said upper ends 46 and 47, of the plates 40 and 41, is a sprocket wheel 48, and between the lower ends 49' and 50 of the plates is another sprocket wheel 51, over which wheels is trained a sprocket chain 52. Both of the wheels 48 and 51, are provided with square apertures 53 and 54, respectively, the former to receive the square shank 55, of a crank 56, provided with a handle 57, and by which the wheel 48, is turned. The crank 56, is freely removable to save space in a tool box. The aperture 54, is to receive the shank 37 of the socket wrench driver 38.

30 It is thought that persons skilled in the art to which the invention relates will be able to obtain a clear understanding of the invention after considering the description in connection with the drawings. Therefore, a more lengthy description is regarded as unnecessary.

Changes in shape, size and rearrangement of details and parts such as come within the purview of the invention claimed may be resorted to, in actual practice, if desired.

40 Having now described my invention that which I claim as new and desire to secure by Letters Patent is:

1. A wrench of the kind described, comprising a pair of complementary cylinder forming members, each of said members having an externally and longitudinally tapered portion, a shank rotatable therein and terminating in a worm, complementary bearings projecting from one pair of corresponding ends of said members and a worm gear mounted therein having a socket, the tapered portion increasing in size toward said ends, means for securing said members together comprising a thimble mounted on the upper end of the members and a slidably collar on said members and shaped to co-act with the tapered

portion for temporarily holding the members together, allowing quick manual assembly and disassembly of the wrench.

2. A wrench of the kind described, comprising a pair of complementary cylinder forming members, each of said members having an externally and longitudinally tapered portion, a shank rotatable therein and terminating in a worm, complementary bearings projecting from one pair of corresponding ends of said members and a worm gear mounted therein having a socket, the tapered portion increasing in size toward said ends, other bearings associated with said shank and adapted to be carried therewith when the wrench is disassembled, means for securing said members together, and said means comprising a thimble mounted on the upper end of the members and a slidable collar on said members and shaped to co-act with the tapered portion for temporarily holding the members together, allowing 20

quick manual assembly and disassembly of the wrench.

BENJAMIN H. LYBYER.
